US00D623594S

(12) **United States Design Patent**
Akana et al.

(10) **Patent No.:** US D623,594 S
(45) **Date of Patent:** ** Sep. 14, 2010

(54) **POWER PLUG**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Danielle De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/345,427**

(22) Filed: **Oct. 15, 2009**

(51) LOC (9) Cl. **13-03**

(52) U.S. Cl. **D13/138.2**

(58) **Field of Classification Search** **D13/138.1, D13/138.2, 139.1, 139.2, 139.3, 139.4, 139.5, D13/139.6, 139.7, 139.8, 137.1, 137.2, 137.3, D13/137.4, 107, 108, 110, 133, 146, 151, D13/152, 153, 156, 162, 162.1, 163, 171, D13/177; 174/66, 202, 206, 53, 59, 60; 363/146, 363/15, 34; 320/111, 114, 115; 439/108, 439/172, 173, 344, 373**

(57) **CLAIM**

The ornamental design for a power plug, as shown and described.

DESCRIPTION

FIG. 1 is a front perspective view of a POWER PLUG showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing is for the purpose of illustrating environmental structure and forms no part of the claimed design. The light gray shade lines on the surface portions indicate contour and not surface decoration.
